US00D841078S

(12) **United States Design Patent** (10) **Patent No.:** **US D841,078 S**
(45) **Date of Patent:** **** Feb. 19, 2019**

(54) **SMART GLASSES**

(71) Applicant: **HiScene Information Technology Co., Ltd.**, Shanghai (CN)

(72) Inventor: **Chunyuan Liao**, Shanghai (CN)

(73) Assignee: **HISCENE INFORMATION TECHNOLOGY CO., LTD.**, Zhangjiang Hi-Tech Park, Shanghai (CN)

(**) Term: **15 Years**

(21) Appl. No.: **29/588,455**

(22) Filed: **Dec. 21, 2016**

(30) **Foreign Application Priority Data**

Jun. 28, 2016 (CN) 2016 3 0286810

(51) **LOC (11) Cl.** **16-06**

(52) **U.S. Cl.**

USPC **D16/309**

(58) **Field of Classification Search**

USPC D16/101, 300–342, 900; D29/109–110; D21/483, 659–661; D14/372; 351/41, 351/44, 45–48, 51–52, 62, 158, 92, 351/103–123, 140–153, 63, 59; 2/13, 15, 2/426–432, 447–449, 441, 434–437

CLAIM

The ornamental design for a smart glasses, as shown and described.

DESCRIPTION

FIG. 1 is a perspective view of the smart glasses showing our new design.

FIG. 2 is a front view of the smart glasses shown in FIG. 1.

FIG. 3 is a rear view of the smart glasses shown in FIG. 1.

FIG. 4 is a left view of the smart glasses shown in FIG. 1.

FIG. 5 is a right view of the smart glasses shown in FIG. 1.

FIG. 6 is a top view of the smart glasses shown in FIG. 1; and,

FIG. 7 is a bottom view of the smart glasses shown in FIG. 1.

The elements shown in broken lines form no part of the claimed design.

1 Claim, 5 Drawing Sheets
